UNITED STATES PATENT OFFICE.

SOLOMON LUBER, OF NEW YORK, N. Y., ASSIGNOR TO STANDARD SOLOPHONE MFG. CO. INC., OF NEW YORK, N. Y., A CORPORATION OF NEW YORK.

GAME DEVICE.

Application filed January 19, 1925. Serial No. 3,234.

To all whom it may concern:

Be it known that I, SOLOMON LUBER, a citizen of Poland, residing at New York city, county of New York, and State of New York, have invented certain new and useful Improvements in Game Devices, of which the following is a specification.

This invention relates to game devices and in particular to a ball rolling or ball projecting game in which the skill of the player may be tallied in points.

A particular object of the invention is to provide a game device consisting of a panel which is either laid upon the ground or placed in vertical position and toward which balls or game pieces are projected or rolled to enter the openings in the panel and thus score points for the player.

A further object of the game is to provide a game board which will retain the game pieces, when said board is used flat upon the ground or disposed in vertical relation thereto.

A still further object is to provide a game device which will be amusing and which can be used in or out of doors and which can be manufactured at small cost with a resulting benefit to the purchaser.

Referring to the drawing wherein I have shown a preferred embodiment of my invention—

Figure 1 is a view in front elevation of the game device set up in position for use with a ball projector;

Figure 2 is a view in side elevation of the device as illustrated in Figure 1;

Figure 3 is a section taken on the line 3—3 of Figure 1 and shows the method of attachment of the ball retaining cup which forms a feature of my invention;

Figure 4 is a view in perspective of a modified form of my invention which is adapted to be laid on the ground to receive balls or game pieces tossed or rolled towards it; and

Figure 5 is a section taken on the line 5—5 of Fig. 4 showing the construction of the device.

Referring to the drawing in detail 5 indicates generally a game board which is made up of any stiff material, metal being preferable on account of its resiliency and durability, having a front face piece 6, and, downwardly bent integral side portions 7 and a top or end portion 8. It is to be un-

derstood that the device while shown as standing up in Figures 1 and 2 can be laid upon the ground and therefore the side pieces 7 are shaped to give the face piece or body 6 an inclined position, so that when said side pieces are resting on the ground the balls may be rolled up the incline to drop into any hole, there being shown three of these openings 9, 10 and 11 for illustration, the hole 9 having a value of say ten points as shown by the numeral ten printed on the face piece adjacent the hole, while the openings 10 and 11 have each a value of five as similarly indicated. Any number of holes may be provided and have printed adjacent thereto any value.

The side pieces 7 have pivoted thereto as at 12 the supports 13 which are so riveted as to be frictionally held in any open position whereby they will retain the game board in angular or vertical position, the position illustrated in Figure 2 being the one used when the balls are projected toward the same by a gun or other device.

In order to prevent the balls from escaping when they enter a hole and to also make the fact known that a point has been scored, I provide behind each opening a cup member 14 which, as shown in Figure 3 is hinged at its lower edge as at 15 to a struck out portion 16 of the front piece 6, and at its top is bent slightly outward as at 17 to frictionally engage and snap over a lip 18 which is punched out of the front piece 6.

Thus, when a ball is projected through the opening it strikes the cup 14 and disengages the same from the lip 18 to allow the cup to drop to the position shown in outline in Figure 3, and retain the ball. The bottom of the cup may contain a piece of felt or other soft material 19 which will prevent rebound of the ball, the felt having printed thereon an ornamental picture as at 20. It will be understood that the felt may be dispensed with and the picture printed in the bottom of the cup if desired.

In Figures 4 and 5 I have shown a similar construction of game board in which I have omitted the cups 14 and supports 13, the device being adapted for use on the ground and having its face portion 6 inclined and provided with openings 21, the portion 6 having delineated or printed thereon as at 22 the representation of the bottom of a cap, the holes forming what

would ordinarily be the cap opening, so that the balls are rolled along the ground and up the piece 6 into the holes. The height of the piece 6 from the ground is 5 small enough to prevent the escape of the balls once they enter the openings, as shown in outline in Figure 5. The openings are designated with suitable tally numerals as before described.

10 It is evident therefore that I have provided an amusing game device at which balls or game pieces may be rolled or projected to score points for the various players, the most skillful of which will of course 15 obtain the highest score.

Having described my invention what I claim is:—

1. A game device comprising a board having an inclined face with a plurality of 20 openings therein, game piece receptacles hingedly associated with said face adjacent said openings, and means on said face member for releasably holding said receptacles in position to receive a projected game 25 piece.

2. A game device comprising a panel member adapted to be disposed at an angle

when the device is laid on the ground, said panel having openings therein, the borders of said openings being painted to simulate 30 a cap, and numerals on said panel adjacent said openings for representing a score value.

3. A game device comprising a panel having side portions and an end portion, supports pivoted to said side portions whereby 35 the panel may be held in substantially vertical position, the panel having face openings therein, and cup members on the underside of said panel disposed behind said openings.

4. A game device comprising a panel having openings therein, foldable supports disposed at the sides of said panel for holding the same in substantially vertical position, cup members hinged to said panel behind 45 said openings, means for releasably holding the edges of the cup members adjacent the panel whereby the cups will be permitted to swing on their hinges when struck by a projected game piece, a yieldable bottom piece in each of said cups and pictures 50 on said bottom pieces.

SOLOMON LUBER.
